His Attorney.

UNITED STATES PATENT OFFICE

2,615,950

ELECTRIC TERMINAL CONNECTOR

Frederick S. Lamb, Cleveland Heights, Ohio, assignor to General Electric Company, a corporation of New York

Application February 1, 1950, Serial No. 141,788

9 Claims. (Cl. 173—361)

1

My invention relates to electrical connectors of the plug type having protruding contact prongs which are adapted to be inserted into the contact openings of an electrical socket or receptacle. Such plug-type connectors may be used, for example, as a base for electric lamps or similar devices particularly of the low current type, or as an attachment plug for electric cords.

It is an object of my invention to provide a prong-type electric terminal connector of simple and relatively inexpensive construction and which may be easily and quickly assembled and connected to the current supply wires of the electric lamp, cord, or other device to which it is attached.

Another object of my invention is to provide an electric terminal connector or plug of the above type having mechanical, i. e., solderless, electrical connections of good electrical properties between the connector prongs and the current supply wires of the device to which the connector is attached.

In accordance with the invention, an electric terminal connector such as a lamp base or electric cord plug is provided with projecting contact prongs or blades each formed of a strip of suitable material, such as brass, which is secured to an insulative wall portion of the plug or base body within an opening therein and which extends outwardly from the wall and is bent back upon itself to form two separated side-by-side leg portions between which the current conductor extends, one of the prong legs having a guide ear pressed outward therefrom to provide a passageway through the prong leg serving to receive and guide the current conductor into the space between the prong legs upon its being threaded through the opening in the insulative wall, the guide ear being pinched against the current conductor to electrically connect the latter to the prong.

Further objects and advantages of my invention will appear from the following detailed description of a species thereof and from the accompanying drawing in which:

Fig. 1 is a sectional view, on an enlarged scale, of an electric incandescent lamp provided with a terminal connector or base according to the invention; Fig. 2 is an exploded view of the base shown in Fig. 1 prior to assembly of the parts thereof, with the base shell shown partly broken away; Fig. 3 is a perspective view, partly broken away, of the base according to the invention; and Fig. 4 is a fragmentary sectional view on the line 4—4 of Fig. 1.

2

While the invention is shown in the drawings as employed in a base for an electric incandescent lamp, it will be obvious that it may be applied as well to bases for electric glow lamps or other discharge devices, or to a terminal connector or attachment plug cap for electric cords and the like.

Referring to the drawing, the lamp there shown comprises a hermetically sealed glass envelope or bulb 1 having a reentrant stem 2 provided with a press or seal portion 3 through which are sealed a pair of lead-in or current supply conductors or wires 4, 4. Disposed within the bulb 1 is a light source comprising a tungsten filament 5 electrically connected at its ends to the lead-in wires 4 and supported in position within the bulb by a plurality of support wires 6 anchored in a glass arbor 7 extending inwardly of the bulb from the stem press 3. The bulb 1 is exhausted and, if desired, filled with a suitable gas through an exhaust tube 8 communicating with the interior of the bulb, which tube is afterwards sealed or tipped-off, as indicated at 9, to hermetically seal the bulb.

Suitably secured to the neck end of the bulb 1, as by basing cement 10 for instance, is an electric terminal connector or base 11 according to the invention and comprising a cup-shaped body member 12 having a cylindrical shell portion 13 and an insulative end wall portion 14 which may be made of any suitable insulating material such as glass, porcelain, molded plastic, or the like. Projecting endwise from the end wall 14 and securely fastened thereto is a pair of contact prongs 15, 15 to which the lead-in wires 4 are connected.

In accordance with the invention, the said contact prongs or blades 15 are formed of relatively stiff or rigid metal strip of suitable character such as, for example, spring brass or bronze, and having a thickness of the order of .025 inch and a width of around $\frac{1}{4}$ inch or so. As shown in Fig. 2, the metal strip forming each prong 15 is bent back upon itself to form two side-by-side and slightly diverging leg portions 16, 17 joined by a bent outer end or bight portion 18. The prongs 15 are securely fastened in place on the base end wall 14 with their bent or bight ends 18 outward and with one leg portion fixedly secured against transverse movement and the other leg portion free to be moved transversely. For this purpose, one leg 16 is made longer than the other leg 17 and is formed with an inner end portion 19 which is of reduced width to form abutment shoulders 20 at each side of the strip.

The said inner end portion 19 is also longitudinally slotted inward from the end thereof, as indicated at 21, to form three locking tongues or tabs 22, 23, and 24, the center one 24 of which is preferably of slightly greater width than the outer tongues 22, 23. The slotted ends 19 of the prong legs 16 fit snugly within respective slots or openings 25 in the insulative wall 14 which slots, as shown, preferably extend parallel to one another so as to orient the prongs in the 10 said wall with their flat sides parallel. Also, as shown, the two prongs 15 are preferably positioned in the slots 25 with their shorter or bent leg portions 17 facing each other.

The narrowed end portion 19 of each prong leg 16 is of a length such that when it is inserted into the slot 25 with the shoulders 20 thereon butted up against the outer side 26 of the wall 14, the tongues 22, 23, and 24 will project inwardly beyond the inner side 27 of the said wall. The prong legs 16 are secured or staked in place within the slots 25 by bending the inwardly projecting tongues 22, 23, and 24 over the inner side 27 of the wall 14 with the shoulders 20 abutted against the outer side 26 of the wall, the two outer tongues 22 and 23 preferably being bent in one direction and the center tongue 24 being bent in the opposite direction, as shown. The prong legs 16 are thus fixedly anchored in the insulative wall 14 against transverse movement. The other prong legs 17, however, terminate just short of the outer side 26 of the wall 14 so as to be freely movable transversely toward the anchored legs 16.

For making the connection of the lead-in wires 4 to the contact prongs 15, the slots 25 in the wall 14 are each provided with a recess or enlargement 28 in one of their side walls through which recesses the lead-in wires 4 extend to the exterior of the base. As shown, the recesses 28 are preferably formed in the distal side walls of the two slots 25. The said lead-in wire recesses or passageways 28 are flared out toward the inner side 27 of the wall 14, as indicated at 29, in order to facilitate insertion or threading of the lead-in wires 4 therethrough during the assembly of the base 11 onto the bulb 1.

The lead-in wires 4 extend through respective passageways or apertures 28 to the exterior of the base wall 4 where they are fastened to the associated contact prongs 15 to provide the electrical connection therebetween. For this purpose, the fixedly anchored leg 16 of each prong is formed, immediately outward of the base wall 14, with a pocket-like lug or ear 30 pressed outwardly from the metal strip to provide a passageway 31 therethrough which faces and is directly opposite the lead-in wire aperture or passageway 28 in the base wall 14 so as to receive and guide the lead-in wire 4 into the space between the prong legs 16, 17 upon being threaded through the said wall aperture 28 from the inside of the base. The portion of the lead-in wire 4 which extends through the passageway 31 formed by the pressed-out ear 30 is pinched between the rim 32 of the ear and that portion 33 of the prong leg 16 immediately inward of the ear 30 (i. e., that portion of the prong leg bordering the shear cut of the lug rim 32) to thereby securely fasten and electrically connect the wire to the 70 prong. The pinching of the wires 4 to the prongs 15 may be effected simply by positioning each contact prong between the jaws of a suitable pinching tool or pliers and closing the jaws to apply pressure to the prong legs 16, 17 at the 75

region of the ear 30, as indicated by the arrows in Fig. 1, so as to squeeze the ear 30 against the lead-in wire 4 and pinch it in place.

To facilitate threading of the lead-in wire 5 through the ear passageway 31, and to aid in preventing the cutting or severing of the lead-in wire, during the pinching thereof, by the sheared edges of the prong passageway 31, which edges are apt to have sharp burrs thereon as a consequence of the pressing out operation by which the ears or lugs 30 are formed, the portion 33 of the prong leg 16 immediately inward of the lug or ear 30 is pressed slightly inward, i. e., in a direction opposite to the direction in which the ear 30 is pressed from the prong leg, to form a bent tongue as shown in Fig. 1. Such bending of the metal inward at 33 tends to prevent the subsequent pinching of the lead-in wire 4 so tightly as to cause the cutting thereof and, in addition, results in the formation of a larger and better-shaped passageway 31 which permits easier insertion and threading therethrough of the lead-in wires 4. To assure a positive and secure pinching of the lead-in wire 4 between the ear 30 and the bent tongue 33, the free or spring leg 17 of the prong should extend inwardly beyond the ear 30 and the wire-pinching edge of the tongue 33 so as to engage the tongue and close it against the lead-in wire when the prong legs are squeezed between the jaws of the pinching tool.

From the above, it will be evident that the base according to the invention is of simple and relatively inexpensive construction and can be 35 assembled and the electrical connections made to the contact prongs thereof in a simple, easy and quick manner, without the need of any soldering operations whatsoever. When plugged into a cooperating socket, the movable prong legs 40 17, by virtue of their being in the nature of spring arms, are pressed by the socket contacts toward the fixed prong legs 16 thus squeezing the portion of the conductors 4 therebetween and further assuring a good electrical connection between the conductors and the prongs. As shown, the prong legs 16, 17 may be provided with circular apertures or holes 34 adjacent their outer ends for the purpose of accommodating therein the usual protuberances or dimples which are normally present on the spring contacts of conventional type sockets or receptacles into which the base or terminal connector according to the invention is adapted to be plugged.

Although a preferred embodiment of my invention has been disclosed, it will be understood that the invention is not to be limited to the specific construction and arrangement of the parts shown but that they may be widely modified within the spirit and scope of my invention as defined by the appended claims.

What I claim as new and desire to secure by Letters Patent of the United States is:

1. An electrical connector comprising a body member provided with a one-piece insulative wall portion having an opening therethrough, and a contact prong comprising a strip of metal 65 secured to the said wall and extending outwardly therefrom and bent back upon itself to form a two-legged prong, said prong having portions thereof outwardly adjacent said wall spaced apart laterally of the prong to provide a space therebetween positioned directly opposite and opening toward the said wall opening so as to receive a current conductor upon its being inserted straight through the said wall opening

from the inner side of said wall, said prong portions being relatively deformable to pinch the said conductor therebetween, one of the legs of said prong being anchored in said wall against transverse movement and the other of said legs being transversely movable toward and coextensive with at least the major portion of the protruding length of the anchored leg.

2. An electrical connector comprising a body member provided with a one-piece insulative wall portion having an opening therethrough, and a contact prong comprising a strip of metal secured to said wall within the said opening therein and extending outwardly therefrom and bent back upon itself to form a two-legged prong, said prong having portions thereof outwardly adjacent said wall spaced apart laterally of the prong to provide a space therebetween positioned directly opposite and opening toward the said wall opening so as to receive a current conductor upon its being inserted straight through the said wall opening from the inner side of said wall, said prong portions being relatively deformable laterally of the prong to pinch the said conductor therebetween, said prong further having locking shoulders thereon engaging the inner and outer sides of said wall to longitudinally fix the prong in position on said wall, one of the legs of said prong being anchored in said wall against transverse movement and the other of said legs being freely movable transversely toward and coextensive with at least the major portion of the protruding length of the anchored leg.

3. An electrical connector comprising a body member provided with an insulative wall portion having an opening therethrough, and a contact prong comprising a strip of metal secured to the said wall within the said opening and extending outwardly from the wall and bent back upon itself to form two separated and approximately side-by-side leg portions, one of said prong leg portions being anchored in said wall against transverse movement and being formed, outwardly adjacent said wall, with a pocket-shaped ear pressed outwardly from said leg portion to one side thereof and closely adjacent said wall to provide a passageway therethrough facing and directly opposite the said wall opening and proportioned to receive a current conductor upon its being inserted straight through said opening from the inner side of said wall, said ear being deformable relative to said leg portion to pinch the conductor therebetween, and the other of said prong leg portions being transversely movable towards the anchored leg portion and extending back along the other side of the anchored leg portion a distance to at least overlap and conceal the exposed outer end of the said current conductor when inserted and clamped in place in said passageway.

4. An electrical connector comprising a body member provided with an insulative wall portion having a slot therethrough formed with a recess in one side wall thereof, and a contact prong comprising a strip of metal snugly fitting and securely locked within the said slot to firmly anchor it to said wall and extending outwardly from the wall and bent back upon itself to the side away from the recessed side of said slot to form two separated and approximately side-by-side leg portions, the anchored leg portion of said prong being formed, outwardly adjacent said wall, with a pocket-shaped ear pressed outwardly from said leg portion to the same side as the recessed side

of the slot to provide a passageway therethrough facing and directly opposite the said recess in the slot and proportioned to receive a current conductor upon its being inserted straight through said recess from the inner side of said wall, said ear being deformable relative to said leg portion to pinch the conductor therebetween, and the other of said prong leg portions being freely movable transversely towards the anchored leg portion and extending back along the anchored leg portion a distance to at least overlap and conceal the exposed outer end of the said current conductor when inserted and clamped in place in said passageway.

5. An electrical connector comprising a body member provided with an insulative wall portion having an opening therethrough, and a contact prong comprising a strip of metal secured to the said wall within the said opening and extending outwardly from the wall and bent back upon itself to form two separated and approximately side-by-side leg portions, one of said prong leg portions being anchored in said wall against transverse movement and being formed with an ear pressed outwardly from said leg portion to provide a passageway therethrough facing and directly opposite the said wall opening for receiving a current conductor upon its being threaded through said opening, said anchored leg portion also having the metal thereof immediately inward of said ear pressed out in a direction opposite to said ear, the other of said prong leg portions extending inwardly beyond said ear but terminating short of said wall so as to be freely movable transversely towards the anchored leg portion.

6. An electrical device having a terminal connector comprising a body member provided with a one-piece insulative wall portion having an opening therethrough, a contact prong comprising a strip of metal secured to the said wall within the said opening therein and extending outwardly therefrom and bent back upon itself to form a two-legged prong, said prong having portions thereof outwardly adjacent said wall spaced apart laterally of the prong to provide a space therebetween positioned directly opposite and opening toward the said wall opening so as to receive a current conductor upon its being inserted straight through the said wall opening from the inner side of said wall, and a current conductor extending through said opening into the said space between the said prong portions and pinched therebetween, one of the legs of said prong being anchored in said wall against transverse movement and the other of said legs being transversely movable toward and coextensive with at least the main portion of the protruding length of the anchored leg.

7. An electric lamp comprising an envelope, an electric energy translation element in said envelope, current conductors connected to said translation element and sealed through said envelope to the exterior thereof, and a base secured to said envelope and comprising an insulative wall portion having a plurality of openings through which the said conductors extend, and a plurality of contact prongs each comprising a strip of metal secured to the said wall within respective ones of said wall openings and extending outwardly from the wall and bent back upon itself to form a two-legged prong, each said prong having portions thereof outwardly adjacent said wall spaced apart laterally of the

prong to provide a space therebetween positioned directly opposite the respective wall opening so as to receive a current conductor upon its being inserted straight through the said wall opening from the inner side of said wall, said current conductors extending into the said space between and being pinched between the said portions of the respective prongs to electrically interconnect the same, one of the legs of each prong being anchored in said wall against transverse movement and the other of said legs being transversely movable towards the anchored leg.

8. An electrical device having a terminal connector comprising a body member provided with an insulative wall portion having a plurality of openings therethrough, a plurality of contact prongs each comprising a strip of metal secured to the said wall within a respective one of said wall openings and extending outwardly from the wall and bent back upon itself to form two separated and approximately side-by-side leg portions, one of the leg portions of each prong being anchored in said wall against transverse movement and being formed, outwardly adjacent said wall, with an ear pressed outwardly from said leg portion to provide a passageway therethrough facing and directly opposite the respective wall opening, the other leg portion of each prong extending inwardly beyond said ear and being freely movable transversely toward the anchored leg portion, and a plurality of current conductors extending through respective ones of said wall openings and through the ear passageway in the associated prong and pinched between the said ear and the body of the prong to electrically interconnect the conductors to the respective prongs.

9. An electrical device comprising an envelope, an electric energy translation element in said envelope, current conductors connected to said translation element and sealed through said envelope to the exterior thereof, and a base secured to said envelope and comprising an insula-

5 tive wall portion having a plurality of openings through which the said conductors extend, and a plurality of contact prongs each comprising a strip of metal secured to the said wall within a respective one of said wall openings and extending outwardly from the wall and bent back upon itself to form two separated and approximately side-by-side leg portions, one of the leg portions of each prong being anchored in said wall against transverse movement and being formed, outwardly adjacent said wall, with an ear pressed outwardly from said leg portion to provide a passageway therethrough facing and directly opposite the respective wall opening, the other leg portion of each prong extending inwardly beyond said ear and being freely movable transversely toward the anchored leg portion, said current conductors extending through the ear passageway in respective prongs and being pinched between the said ear and the body of the prong to electrically interconnect the conductors to the respective prongs.
